UNITED STATES PATENT OFFICE.

JOSEPH M. KAISER, OF CHICAGO, ILLINOIS.

DESIGN FOR A MATCH-SAFE.

SPECIFICATION forming part of Design No. 33,539, dated November 13, 1900.

Application filed September 17, 1900. Serial No. 30,362. Term of patent 3½ years.

To all whom it may concern:

Be it known that I, JOSEPH M. KAISER, a citizen of the United States, residing at Chicago, in the county of Cook and State of Illinois, have invented and produced a certain new, original, and useful Design for a Match-Safe, of which the following, when taken in connection with the drawings accompanying and forming a part hereof, is a full and complete specification.

In the drawings referred to, Figure 1 is a top plan view of a match-safe, showing my new design. Fig. 2 is a bottom plan view thereof. Fig. 3 is a front elevation thereof, and Fig. 4 is a side elevation.

As shown in the drawings, the leading or material feature of my design consists of a contour-line, a series of lines, indentations, corrugations, and marks disposed in the several figures of the drawings to obtain a recognizable representation of a frog, with its hind and fore legs drawn close to the body, its mouth closed, and its eyes open. The un-

evenness of the back of a frog is imitated by the several lines, indentations, corrugations, and marks referred to, as is also the smooth under side of a frog.

In the drawings, wherein a reference-letter representing a given part is used to indicate such part throughout the several views, A is the back of the frog; a a, the fore legs; a' a', the hind legs; B, the eyes, and C the mouth.

D is the under side of the frog, and E E F F are the fore and hind feet, respectively.

It is apparent that this design is also applicable to a coin-holder and other similar articles.

Having thus described my invention, what I claim as new, and desire to secure by Letters Patent, is—

The design of a match-safe, substantially as described and shown.

JOSEPH M. KAISER.

In presence of—

A. M. STEELE,
NATHAN EISEMAN.
